UNITED STATES PATENT OFFICE

ALLAN F. MARTIN, OF ROCHESTER, NEW YORK, ASSIGNOR TO BAUSCH & LOMB OPTICAL COMPANY, OF ROCHESTER, NEW YORK, A CORPORATION OF NEW YORK

ARC LAMP

Application filed February 9, 1925. Serial No. 7,796.

The present invention relates to arc lamps, and has for its object to provide improvements in lamps of this kind, particularly with respect to the feeding means for the electrodes.

Another object of the invention is to provide a continuous and positive driving connection for the electrodes together with improved operating means for advancing the same in the direction desired.

Another object of the invention is to provide an arc lamp adapted to be economically constructed and operated, having cooperating actuating devices for feeding the carbons, arranged to operate independently and permitting the driven parts to be returned to initial starting position without interfering with the driving or actuating devices.

To these and other ends the invention resides in certain improvements and combinations of parts, all as will be hereinafter more fully described, the novel features being pointed out in the claims at the end of the specification.

In the drawings:—

Figure 1 is a side elevation of a machine embodying one form of the invention;

Figure 2 is a sectional elevation taken on line 2a—2a of Figure 3;

Figure 3 is a top plan view of the lamp;

Figure 4 is a sectional plan taken on line 4a—4a of Figure 2;

Figure 5 is a fragmentary sectional plan taken on line 5a—5a of Figure 2;

Figure 6 is a sectional plan taken on line 6a—6a of Figure 2, and

Figure 7 is a diagrammatic view illustrating the continuous chain drive shown in Figure 2.

Similar reference numerals throughout the several views indicate the same parts.

The present arc lamp is shown in connection with a projection apparatus for microscopic projection work whereby to illustrate one of a number of different kinds of machines with which the invention may be used. The projection apparatus is illustrated generally at 10 and includes a frame

11 and an upstanding bracket 12 thereon

carrying an objective lens holder 13 at one side thereof and a clamping member 14 at its opposite side which is adapted to engage an extension 15 on a lamp box 16 to support the latter as shown in Figure 1. The lamp box preferably forms a support for the feeding mechanism which advances the electrodes 17 and 18 into the box through the openings 18a and 19 thereof as shown in Figure 2, the box having a chimney 20 with a circuitous passageway 21 for the escape of the products of combustion of the burning electrodes and also having adjustable closures or windows 22 through which the burning carbons may be viewed and also through which air may be admitted in addition to the supply passing through the openings 18a and 19.

The electrodes and the feeding devices therefor are mounted upon a pair of spaced plates or frame members 23 and 24, the upper left hand corners of which project into the lamp box as shown in Figure 2, being suitably connected therewith and supported thereon preferably by means of the downwardly projecting lugs 25 and the screws 26 extending into said plates.

The horizontally disposed electrode 17 is removably attached to a suitable holder 27 and the vertical electrode 18 to a similar holder 28, these holders being slidably disposed preferably upon a pair of horizontal guides 29 and a pair of vertical guides 30, respectively. The outer ends of the guide rods 29 are suitably connected with a member 31 forming a spacer between the plates 23 and 24 and the vertical guide rods 30 have their outer ends suitably connected with a member 32 forming a spacer between the lower edges of the plates, as shown in Figure 2. Both sets of guide rods have their inner or adjacent ends anchored in a block 33 forming a spacer between the upper left hand corners of said plates, the block 33 being preferably constructed of a suitable heat resisting material, such as fire-clay, on account of its proximity to the arc, the block being suitably held preferably by a pin 34, the ends of which are supported by the side plates 23 and 24.

The means for advancing the holders 27

and 28 preferably comprises a flexible operating member 35 in the form of a continuous chain or like connection, with means for positively driving the same which will hereinafter be described. The chain or flexible connection is extended over a series of pulleys or rollers constituting the upper and lower rollers 36 and 37, respectively, and a pair of intermediate rollers 38 and 39 adjacently mounted upon a support 40 which is suitably secured between the plates 23 and 24 as shown in Figure 5. The rollers 36 and 37 are carried by the transversely extending supports 41 and 42, respectively, the ends of which are suitably secured upon the side plates 23 and 24. The chain is directly connected with the carbon holders 27 and 28, as by means of the studs 43, so that it will advance each at the same rate of speed and thereby maintain their free ends at the desired distance apart. The chain is also carried over a driving sprocket indicated at 44 which has a hub 45 rigidly connected with a driving shaft 46 which may be driven by any suitable means. The driving shaft 46 is preferably driven by a suitable clock mechanism disposed in a casing 47 which is preferably mounted upon the outer face of the plate 24 and secured thereon by the screws 48. The clock is provided with the usual winding stem 49 and lever 50 for regulating its speed. The clock may be conveniently started or stopped by pressing a plunger 51 which is spring returned and provided with a lateral extension, not shown, for engaging the teeth of the balance wheel to both start and stop the same as desired. The shaft 46 is so connected with the clock driving mechanism as to be revoluble in a direction reverse to the direction in which it is normally driven without interfering with the operation of the clock, whereby the operator by turning the hand wheel 52 counterclockwise may reverse the movement of the chain and return the holders 27 and 28 to their initial starting position as shown in Figure 2.

In addition to the clock mechanism for positively driving the continuous chain 35 I provide an actuating spring 53 preferably wound upon a support 54 and having an arm-like portion 55 looped at 56 to loosely engage a stud 57 projecting from the holder 28 carrying the vertically disposed electrode 18, said looped end being free to slide on the stud 57 as the holder 28 is moved upwardly with the electrode. The spring 53 tends to raise the arm 55 thereby acting to lift the holder 28, which by reason of the fact that it is connected with the chain exerts a pull thereon in an upward direction, thereby cooperating with the clock mechanism in advancing the electrodes and thus reducing the load on the clock mechanism. The spring not only serves as a direct means for exerting a lifting force upon the holder 28 and

the electrode carried thereby, but at the same time assists in advancing the holder 27, through the pull which it exerts upon the chain in the direction of its movement.

While the clock spring may be made strong enough to advance the electrodes independently of any other lifting mechanism it is desirable to use a relatively small clock and provide means adapted to cooperate therewith in moving the parts in the direction desired. As the electrodes are gradually burned away, the load becomes lighter the nearer the holders approach their destination and likewise the driving springs become weaker as they unwind, whereby the proportion of lifting power to the load to be lifted remains substantially constant.

Connected with the holders 27 and 28, as indicated at 57a in Figure 6, are flexible cables 58 and 59, the outer ends of which are connected with binding posts 60 and 61, respectively, which are suitably insulated from the plates 23 and 24 and preferably constitute extensions on the spacing members 31 and 32. Any suitable electric current supply source, not shown, may be provided and connected with said binding posts through the medium of suitable conductors.

The means by which reversal of the shaft 46 is effected without reversing the clock mechanism is shown in Fig. 3 along with certain of the operating parts of the clock. These include the main spring 62 on the winding shaft 63 and the driving gear 64 on the same shaft. The driving gear engages a pinion loosely mounted upon the shaft 46 which comprises the spaced end plates 65 and 66 and the pins 67 extending therebetween. The plate 66 is connected with and drives a gear 68, also loose on shaft 46, and which in turn drives the remaining gears of the operating parts, (not shown) for actuating the escapement wheel of the clock. The driving means for the shaft 46 comprises a clutch thereon frictionally driven by the plates 65, the clutch embodying a bowed or dish-like spring 69 urged into engagement with said plate by a collar 70 fixed on the shaft 46. The pressure exerted by the spring and the resultant friction afforded by the parts associated therewith is sufficient to drive the shaft 46 and the chain arranged to be driven thereby. However, in manually reversing the shaft as by turning the hand wheel 52 to reverse the movement of the chain, the friction exerted by the clutch on the plate 65 is not sufficient to cause reverse rotation of the driving gear 64 against the action of the main spring 62. Consequently the clock mechanism is not reversed and is in no way interfered with by manual rotation of the shaft 46 when operating it to return the carbon holders to their extreme outer position.

I claim as my invention:

1. In an arc lamp, a frame, a pair of electrodes mounted for movement upon the frame one toward another, a flexible driving connection for simultaneously advancing the electrodes toward each other, and independent devices for driving said connection, one including a rotary part for advancing the connection and the other a yieldable element arranged to urge the connection in the direction of its movement by the rotary part. 5
2. In an arc lamp, a frame including guides, holders slidably mounted upon the guides, electrodes carried by the holders, a series of rollers upon the frame, a flexible operating connection extending over the rollers and engaging the holders, and independent operating devices for said connection cooperating to effect advancement of the holders toward a common point, one of said devices including a rotary driving part for the connection and the other comprising an arm with means for swinging it about a point spaced from the connection. 10
3. In an arc lamp, a frame including guides, holders slidably mounted upon the guides, electrodes carried by the holders, a series of rollers mounted upon the frame, a flexible operating connection extending over the rollers and connected with the holders, a clock mechanism adapted to drive said connection, and spring means cooperating with the clock mechanism and operating independently thereof to drive said connection. 15
4. In an arc lamp, a frame comprising spaced connected plates, angularly disposed guides mounted between said plates, separate holders mounted to travel upon the guides, electrodes carried by the holders, a continuous chain disposed between the plates to advance the holders toward a common point, and separate devices for driving the chain operable upon the latter at different points in its path of movement, one of said devices including a power driven element and the other comprising a spring coiled upon a support and having a swingingly mounted operating portion connecting with the chain. 20
5. In an arc lamp, a frame comprising spaced connected plates, angularly disposed guides mounted between said plates, separate holders mounted to travel upon the guides, electrodes carried by the holders, a flexible operating connection for the holders disposed between the plates and adapted to advance the holders toward a common point, clock mechanism operating upon said connection to effect movement of the holders, a member carried by one of the holders and a swingingly mounted spring actuated arm having its free end in sliding engagement with said member and operating thereon to assist the clock mechanism in advancement 25 of said flexible operating connection. 25
6. In an arc lamp, a frame including guides, holders slidably mounted upon the guides, electrodes carried by the holders, a series of rollers upon the frame, a flexible operating connection extending over the rollers and engaging the holders, driving means for the connection, and auxiliary driving means for the connection comprising a spring operatively associated with one of the holders and tending to lift the same. 30
7. In an arc lamp, a frame including guides, holders slidably mounted upon the guides, electrodes carried by the holders, a series of rollers upon the frame, a flexible operating connection extending over the rollers and engaging the holders, driving means for said connection, and a spring including an extended arm-like portion engaging one of the holders and cooperating with the driving means to advance said connection. 35
8. In an arc lamp, a frame, a pair of electrodes one of which is horizontally and the other vertically disposed upon the frame for movement toward a common point, holders for said electrodes, a plurality of rollers carried by the frame, a flexible driving element extending over the rollers and operatively engaging said holders, actuating means for said driving element, and a spring including an extended arm-like portion secured to the frame at one end and having its other end connected with and free to move relative to the holder of the vertically disposed electrode. 40
9. In a device of the class described, a lamp housing comprising a body having a portion adapted for connection with a projection apparatus, said body being provided with a chimney and having openings below the chimney in its bottom and one of its vertical walls, a frame depending from and supported by the housing, angularly disposed guides carried by the frame, holders mounted for travel upon the guides toward the housing, angularly disposed electrodes carried by the holders and projecting through said openings into the housing and means for advancing the holders toward the housing. 45
10. In an arc lamp, a frame, holders reciprocally mounted upon the frame, electrodes carried by the holders, a flexible connection on the frame for moving the holders back and forth thereon, a clock mechanism including a train of gears and an arbor, a driving device for the arbor driven by one of the gears, said arbor being reversible without reversing the movement of the gears, and means actuated by the arbor for operating said flexible connection, reversal of the arbor serving to effect reverse movement of the connection and the holders operated thereby. 50
11. In an arc lamp, a frame, spaced hold- 55

ers reciprocally mounted upon the frame each arranged to support an electrode, a flexible operating connection arranged to reciprocate the holders, a clock mechanism including a train of gears and an arbor on which one of the gears is mounted to rotate, driving means for the arbor arranged to be driven by said last gear, the arbor being reversible without reversing said gear, and means on the arbor arranged to drive said flexible connection, reversal of the arbor serving to effect reverse movement of the connection.

12. In an arc lamp, a frame, spaced holders reciprocally mounted upon the frame, a reversible operating device for said holders, a clock mechanism including a train of gears and an arbor on which one of the gears is mounted to rotate, driving means for the arbor arranged to be driven by said last mentioned gear, said driving means permitting reverse movement of the arbor without reversal of said gear and means on the arbor for driving said reversible operating device.

13. In an arc lamp, a frame, holders reciprocally mounted upon the frame, electrodes carried by the holders, a flexible connection on the frame for moving the holders back and forth thereon, a clock mechanism including a train of gears and an arbor, a driving device for the arbor driven by one of the gears said arbor being reversible without reversing the movement of the gears, means actuated by the arbor for operating said flexible connection, reversal of the arbor serving to effect reverse movement of the connection and the holders operated thereby, and yieldable means supplementing the clock mechanism and tending to constantly move the connection in the direction in which it is moved by the clock mechanism to advance the electrodes one toward another.
